HYDRAULICALLY OPERATED PITCH CHANGING MECHANISM

Horace H. Roby, Wichita, Kans., assignor, by mesne assignments, to Robert C. Foulston, W. L. Hartman, and John F. Fitz-Gerald, trustees of Roby, Inc., Wichita, Kans., a corporation of Kansas

Application May 1, 1942, Serial No. 441,346

3 Claims. (Cl. 170—163)

My invention relates to new and useful improvements in hydraulically operated pitch changing mechanism for variable pitch propellers.

If the engine of an airplane is to operate with maximum efficiency, the pitch of the propeller blades must be set in accordance with existing conditions of air density, plane speed, engine speed and power, etc. These conditions vary depending upon whether the plane is taking off or flying level at a substantial altitude. Indeed, these conditions may vary considerably during the course of a long flight depending upon the weather conditions, the character of the country over which the plane is flying, etc. Accordingly, fixed pitch propellers are generally unsatisfactory. It is highly desirable that an adjustable pitch propeller be provided having a maximum and a minimum pitch position and capable of being held at any selected adjusted intermediate position.

For example, it is desirable that the propeller blades be adjusted to a low pitch during the take-off period and adjusted to a high pitch position after the plane has gained altitude and assumed a normal level flight. If the propeller blades are given a low pitch during the take-off, the engine can obtain its most efficient speed substantially immediately, permitting the plane to rise after a relatively short run and to gain elevation essentially rapidly. When taking off, the plane speed is low and there is a heavy load on the propeller. Internal combustion engines do not develop maximum power at slow engine speeds. Therefore, if during the take-off period the pitch of the blades is too high, the resistance offered by the air to rotation of the propeller will hold the engine to a relatively slow speed so that it will be most inefficient when the greatest power is needed.

Also, if the pitch of the propeller blades is too high during the take-off period, the plane will remain on the ground a longer time before attaining flying speed. It is especially desirable in the case of light airplanes and observation, interceptor, scouting and fighter planes that the take-off time be reduced to a minimum.

If the propeller is adjusted and held at a low pitch position, the plane will rise and attain flying speed after a relatively short run. However, after the plane assumes a normal level flight, the resistance offered by the air to propeller rotation is decreased, the load on the engine becomes less and the engine will speed up. The engine must then be throttled down and will produce but a portion of the power of which it is capable. For maximum efficiency, the propeller should be ad-

justed to a high pitch position during normal flight. The propeller blades will then offer sufficient resistance to hold the engine at its normal full power speed.

Furthermore, present day airplanes fly long distances and frequently at high altitudes. When the plane is operated under these conditions, it is often necessary that the propeller blades be held at intermediate positions between the maximum and minimum pitch positions if optimum efficiency is to be realized.

Variable pitch propellers are operated both mechanically and hydraulically. When a mechanical control is used, the propeller blades may be rotated through a predetermined pitch range and held at a selected adjusted position. However, where a hydraulic control is used, it has not been possible to easily position and hold the propeller blades at any selected adjusted intermediate pitch position.

It is therefore an object of my invention to provide a hydraulic control for a variable pitch propeller that may be manually operated to hold the propeller in any selected adjusted position between a maximum and minimum pitch position.

Another object of my invention is to provide a hydraulic control of the above mentioned character that may be easily operated by the pilot when the plane is in flight.

Still another object of my invention is to provide a hydraulic control of the above mentioned character that involves a minimum of working parts to eliminate mechanical troubles as far as possible.

Other objects and advantages of my invention will be apparent during the course of the following description.

In the accompanying drawings forming a part of this specification and wherein like numerals are employed to designate like parts throughout the same,

Fig. 1 is a side elevation of a hydraulically operated pitch changing mechanism embodying my invention, parts being shown in section for clearness of illustration.

Fig. 2 is a fragmentary vertical sectional view, taken on the line 2—2 of Fig. 1.

Fig. 3 is an enlarged vertical sectional view taken on the line 3—3 of Fig. 2.

Fig. 4 is a transverse sectional view taken on the line 4—4 of Fig. 3.

Fig. 5 is a longitudinal sectional view taken on the line 5—5 of Fig. 3, showing an automatic fluid control valve embodying a part of my invention.

Fig. 6 is a vertical sectional view taken on the line 6—6 of Fig. 5.

Fig. 7 is a fragmentary vertical sectional view taken on the line 7—7 of Fig. 6, showing a cam comprising a part of the automatic valve mechanism in a position to close the valve.

Fig. 8 is a view similar to Fig. 7 but showing the cam rotated to a position to open the valve, and

Fig. 9 is a fragmentary view similar to Fig. 3, showing the hydraulically operated pitch changing mechanism without the automatic fluid control valve.

In accordance with this invention, I mount a variable pitch propeller on a conventional crank shaft having a hollow outboard end as shown in Fig. 1. Mechanism is provided for rotating the propeller blades about their axes in response to movement of a piston mounted on the forward end of the crank shaft. A bleed line from the lubricating system of the plane conducts crank case oil into the hollow crank shaft. The pressure developed by the oil pump on the fluid in the crank shaft is sufficient to force the piston outwardly against the forces acting on the rotating propeller blades. A valve manually operable from the cockpit of the plane controls the flow of oil into the crank shaft and also the flow of oil therefrom. By proper operation of the valve, a requisite amount of oil may be forced into the hollow portion of the crank shaft to move the piston a selected distance. An automatic valve mounted in the crank shaft is provided to hold the oil in the piston. The automatic valve is operated by fluid pressure in the crank shaft. Each time fluid under pressure is injected into the crank shaft, the valve is automatically operated. One injection of fluid into the crank shaft moves the automatic valve to a closed position and the next injection of fluid into the crank shaft moves the valve to an open position. Thus, repeated opening and closing of the manually operated valve will cause consecutive injections of fluid into the crank shaft so that the automatic valve may be either opened or closed to either hold or release the oil in the piston. When the automatic valve is closed, the oil is trapped in the piston. When the automatic valve is open, oil trapped in the piston is released. The torque on the propeller blades will then retract the piston and unless checked the propeller blades will continue to rotate until they assume a minimum pitch position.

In the preferred embodiment of my invention shown in the drawings, the numeral 10 designates a tubular crank shaft which projects through the front wall of crank case 11 in the conventional manner. A propeller hub 12 is splined to crank shaft 10 as best shown in Fig. 2. The inner end of hub 12 seats against the tapered surface of holding ring 13 held in position by spacing ring 13a. A sealing ring 13b is in front of ring 13. A cone or holding ring 14 is held tightly against the internal conoidal surface 15 at the forward end of the hub by locking nut 16. Holding ring 13 and locking ring 16 securely hold hub 12 therebetween.

A hollow cylindrical housing 17 is carried by propeller hub 12. The housing is formed in two parts which are held together by bolts 18 and nuts 19. Sleeves 20 are secured to the butt ends of the propeller blades (not shown). On the threaded portions of shanks 20a of sleeves 20 are screwed collars 21. The hub 12 has integral radial spindles 12a which project into the hollow

ends of the shanks 20a, and bearing surfaces for rotation of the sleeves on the spindles is supplied by removable bearing sleeves. Collars 21 have flanges 21a within the housing 17. Thrust bearings 22 are positioned between flanges 21a and the enclosing ends 17a of housing 17. These thrust bearings carry the centrifugal load imposed when the propeller is rotated. The thrust bearings also permit axial rotation of the propeller blades about spindles 12a when the pitch of the blades is changed.

Helical springs 23 are confined between the shoulders 12b of spindles 12a and the shoulder 20b of the outer bearing sleeves. The resilient action of springs 23 urges the propeller blades outwardly and holds the collar flanges 21a against the inner races of thrust bearings 22. Heretofore, it has been customary to use roller bearings in place of springs 23. However, where roller bearings are used, it is necessary to provide for removing play in the bearings by means of shims. This bearing arrangement has proven to be generally unsatisfactory. When a roller bearing assembly of the type shown at 22 is not furnished with resilient means to hold it compactly together, vibrations created by power impulses of the engine cause the balls of the race to chatter and wear the surfaces of the inner and outer races. Thus, the balls pound themselves into the races and a rough bearing is the result. By using springs 23, it is unnecessary to "shim" the bearings with sufficient force to prevent chattering or vibration of the balls. Springs 23 also prevent the flanges 21a from dropping away from thrust bearings 22 when the propeller is at rest.

Surrounding the bases of spindles 12a are ring shaped control arms 24. These arms are journaled for rotative movement about pivot pins 25 which are partially embedded in the hub 12. The arms loosely surround the spindles and the ends thereof adjacent pivot pins 25 are bifurcated to receive pins 26 projecting from the flanges 21a of the propeller collars as shown in Fig. 2. When the control arms are pivoted about pins 25, they will move the propellers through an arc having the center of the pivot pins 25 as a radius. This movement will increase or decrease the pitch of the blades.

Mounted on a forward tubular extension 12c of the hub 12 is a piston 27. Arms 27a integral with the piston are fitted into channels or grooves 12d in the hub and serve to connect with the ends of control arms 24 remote from pivots 25 through pins 26 fastened to the arms by screw bolts shown dotted in Fig. 2. When the piston moves outwardly due to the introduction of hydraulic liquid, the control arms 24 will be pivoted about pins 25 to increase the pitch of the propeller blades. When the piston moves inwardly upon discharge of hydraulic liquid, control arms 24 will be pivoted in the opposite direction about pivot pins 26 to decrease the pitch of the blades. An end enclosure 28 threaded into the tubular extension 12c carries a flexible ring 29 which seals the inner wall of the piston to form a fluid-tight chamber.

The piston is limited in its reciprocating movement by bolt 31. The end of bolt 31 extends through the end of the piston and has a head for adjustment. Passages 29a in the end enclosure 28 around the bolt permit the hydraulic fluid to enter the piston. Hydraulic pressure within the piston will force it outwardly until the head of bolt 31 engages the end enclosure 28. The piston stroke is regulated by adjustment of bolt 31.

The bolt is held in the selected adjusted positions by lock nut 22.

Thus, the stroke of the piston may be easily regulated without dismantling any parts of the mechanism. Inward movement of the piston is limited by abutment of bosses 33 and 34 in which position the hydraulic fluid may freely pass through radial channels 34a thus preventing the formation of a seal between the piston and end enclosure 29.

As a source of hydraulic fluid, oil from the lubricating system is supplied under pressure to the piston by pump 35. This oil pump is conventional in airplanes to circulate the fluid lubricant from a reservoir or sump through the lubricating system. A fragmentary part of the oil circulating system is shown at 36. Oil is bled from the line 36 through pipe 37. This oil passes through valve 38, pipe 39, passage 40 and into the hollow crank shaft through radial passages 10a. The core 38a of valve 38 is manually rotated by control arm 41. A link 42 connects the arm 41 with a control on the instrument board (not shown) within the cockpit of the airplane. The control is preferably located in a position where it may be easily operated by the pilot.

When arm 41 is pushed forwardly, as shown in Fig. 1, passage 38b through the valve core will connect pipe 37 with pipe 39 so that pump 35 forces oil under pressure into the crank shaft. If arm 41 is moved in a reverse direction, the enlarged end of passage 38b will move into register with pipe 39 and pipe 43. Pipe 43 connects valve 38 with the oil sump. When the valve core is in the last mentioned position, pipe 37 is shut off and fluid trapped in the crank shaft and behind the piston will flow through passage 40, pipe 39, valve passage 38b, and pipe 43 to the oil sump or reservoir.

Flow of oil to or from piston 21 through the crank shaft is controlled by a valve designated generally by the numeral 44 having a tubular valve body 45. The forward end of a valve body is fixedly connected to a boss on the hub end enclosure 29. A bearing seal 46 supports the inner end of the valve body against the internal wall of the crank shaft. The valve body is formed in two parts 45a and 45b which are connected by a valve plug 47 shown in Fig. 5. The valve plug has a longitudinal passage 47a which is normally closed by ball valve 48. Helical spring 49 confined between plug 50 and ball valve 48 urges the ball valve to a seated position.

To unseat the ball valve there is located inwardly of plug 47 and within valve body 45 a plunger 51 connected by a restricted neck to hollow open ended reciprocating sleeve 51a shown rectangular in cross section in Fig. 6. A sleeve extension of plug 47 extends into the end of the rectangular sleeve 51a and is surrounded by compression spring 52 which abuts its outer end on plug 47 and its inner end on reciprocating sleeve 51a. Within the rectangular reciprocating sleeve 51a is a cam 54 keyed to a pin 55 between two ratchets 57 and 58. These ratchets have four teeth positioned ninety degrees apart and are staggered with respect to their position on pin 55 so that the teeth of the two ratchets are arranged or spaced forty-five degrees apart. The ends of the pin 55 extend through slots in the side of the reciprocating sleeve and are journaled in the valve body 45 as shown in Fig. 6. Also within the reciprocating sleeve are shoulders or abutments 51b and 51c positioned diametrically opposite each other and located to contact the

teeth of the ratchets on reciprocation of the sleeve. Within the sleeve portion of the plug 47 and extending from the ball valve 48 to the cam 54 is a cam follower pin 55.

Fluid pressure in the crank shaft created by pump 35 moves the plunger 51 forward against the action of spring 52. When the fluid pressure in the crank shaft is cut off by operation of valve 38, spring 52 slides the plunger inwardly against locking ring 53. Each reciprocating of plunger 51 rotates cam 54 ninety degrees. Rotation of the cam actuates the pin 55 to unseat and permit seating of the ball valve 48.

Referring now to Figs. 5 through 8 where is best shown the manner in which the cam 54 is operated and the rotative actuation of the ratchets 57 and 58 and explaining the operation of the valve 44 assuming the cam in the position shown in Figs. 5 and 7, the manual control valve 38 in the position shown in Fig. 1 and that hydraulic fluid is being injected by pump 35; the plunger 51 is moved outwardly by introduction of hydraulic fluid. Abutment 51c during this movement of the plunger 51 contacts the adjacent tooth of ratchet 58 rotating the ratchet and cam forty-five degrees from that shown in Figs. 5 and 7 to a position shown in Fig. 8. As suggested, the teeth of ratchets 57 and 58 are staggered. When the fluid pressure upon valve 51 is released by movement of control valve 38 to connect pipes 39 and 43, the hydraulic fluid moves from the crank shaft toward the sump. Spring 52 urges plunger 51 inwardly and abutment 51b engages the adjacent tooth of ratchet 57 rotating cam 54 an additional forty-five degrees or to a horizontal position parallel with pin 55 when ball valve 48 is at its maximum open position.

With every injection of hydraulic fluid, plunger 51 is forced outwardly against the action of spring 52 and with release of pressure on the hydraulic fluid, plunger 51 moves in a reverse direction due to action of the spring. Both outward and inward movements of plunger 51 cause a forty-five degree rotation of the cam 54, the combined reciprocation causing a ninety degree rotation of the cam due to positioning of the abutments 51b and 51c and the staggered arrangement of the ratchets 57 and 58. As the cam rotates to the forty-five degree position shown in Fig. 8, it will slide pin 55 to move ball valve 48 away from its seat. The fluid then flows from the hollow crank shaft chamber around loosely fitting plunger 51, through slots 48c in the valve body, through ports 47b in plug 47, around the unseated ball valve 48, through passages 47c and 29a and behind piston 21.

After the piston has been moved outwardly a distance sufficient to increase the pitch of the propeller blades a desired amount, it will be necessary to close the ball valve 48 and hold the hydraulic fluid behind the piston. To effect this result, manually operated valve 38 must be actuated one time more to move the cam through ninety degrees when the cam 54 is again in a vertical position as shown in Fig. 5 and ball valve 48 is closed.

Should the pilot desire the propeller pitched to its maximum, movement of the control valve 38 to permit admission of the hydraulic fluid 70 will accomplish this result. If a minimum pitch or feathering of the blades is desired, this is effected by operating the manual control 38 so the hydraulic fluid will drain back into the sump or reservoir and this result is obtained when the cam 54 is in a horizontal position and ball valve

48 is wide open. The retardation of the pitch occasioned by flowing of the hydraulic fluid from behind piston 27 to the sump is relatively slow due to the constricted passages in the piston and valve through which the fluid must pass. Likewise and for the same reason, increasing the pitch is a relatively slow operation permitting actuation of the control valve 38 at any time to give the propeller blades a selected pitch. To maintain the pitch of the propeller in any fixed selected position, the operation is that heretofore described, namely the hydraulic fluid is introduced until piston 27 by means of arms 27a has moved the blades to the desired pitch. Control valve 38 is then actuated to rotate the cam to a position where ball valve 48 is closed and the fluid is trapped behind the piston.

Attention is directed to the fact that the automatic valve 44 is centered within the crank shaft so that every moving part of the valve operates along the center of the crank shaft. Thus, none of the parts will be influenced by centrifugal force.

If it is desired to have only two selected pitch positions of the propeller blades, one for taking off and the other for normal cruising, the hydraulically operated valve 44 may be omitted. If the valve is omitted, the pitch changing mechanism will be as shown in Fig. 9. To give the propeller blades the desired low pitch during the take-off period, manually operated valve 38 is adjusted to connect the line 39 with sump line 43. Fluid pressure in the crank shaft and behind piston 27 will then be released. The wind resistance acting on the propeller blades will provide sufficient torque to move piston 27 inwardly and expel the hydraulic fluid therein. After the plane gains sufficient altitude to assume normal level flight, the pitch of the propeller blades may be increased to the maximum pitch position by operating the manually controlled valve 38 to connect pipes 37 and 39. The crank case oil, acting as the hydraulic fluid, is injected into the crank shaft by pump 35. This fluid enters the piston and forces the same outwardly until its travel is limited by engagement of bolt 31 with member 29. Valve 38 remains open until it is again desired to reduce the pitch of the propeller blades.

It will be readily appreciated, however, that the automatic valve 44 is a desirable feature for the reason that it may be used to hold the piston 27 at a selected adjusted position between the inner and outer limits of its travel. This is a decided advantage. When using valve 44, should the propeller blades be in the maximum pitch position and the blades have been given too much pitch, piston 27 may be easily retracted a slight distance until the propeller blades have the proper pitch.

It may thus be seen that I have achieved the objects of my invention. I have provided a hydraulically operated pitch changing mechanism for variable pitch propellers that may be easily

operated by the pilot. By the use of my mechanism the propeller blades may be held in any selected adjusted position best suited to existing conditions of air density, plane speed and engine speed and power.

It is to be understood that the form of my invention herewith shown and described is to be taken as a preferred example of the same and that various changes in the size, shape and arrangement of parts may be resorted to without departing from the spirit of my invention or the scope of the appended claims.

Having thus described my invention, I claim:

1. In combination with a variable pitch propeller, a hydraulically operated pitch changing mechanism comprising a fluid pressure operated means connected to the propeller blades for adjusting their pitch, a manually operated valve controlling the flow of fluid to and from the fluid pressure operated means, a fluid passage between the manually operated valve and the fluid pressure operated means, and an automatic valve mechanism in said passage, said automatic valve mechanism including a rotatable cam adapted in different adjusted positions to open and close the automatic valve mechanism, and a fluid pressure actuated means operated by successive operations of the manually operated valve cooperative with the cam to move it to said different adjusted positions.
2. In combination with a variable pitch propeller, a hydraulically operated pitch changing mechanism comprising a fluid pressure operated means connected to the propeller blades for adjusting their pitch, a manually operated valve controlling the flow of fluid to and from the fluid pressure operated means, a fluid passage between the manually operated valve and the fluid pressure operated means, and an automatic valve mechanism in said passage, said automatic valve mechanism including a rotatable cam adapted in different adjusted positions to open and close the automatic valve mechanism, a plunger actuated by fluid pressure, and means responsive to movement of the plunger for moving the cam to said different adjusted positions.
3. In combination with a variable pitch propeller, a hydraulically operated pitch changing mechanism comprising a fluid pressure operated means connected to the propeller blades for adjusting their pitch, a manually operated valve controlling the flow of fluid to and from the fluid pressure operated means, a fluid passage between the manually operated valve and the fluid pressure operated means, and an automatic valve mechanism in said passage, said automatic valve mechanism including a rotatable cam adapted to open and close the automatic valve mechanism, ratchet wheels rotatable with the cam, and a fluid actuated plunger having pawls engageable with the said ratchet wheels to rotate the cam.

HORACE H. ROBY.
